UNITED STATES PATENT OFFICE

2,538,920

DISPLAY BAG AND METHOD OF MAKING
THE SAME

Harold F. Shumann, Pittsburgh, Pa.

Application November 18, 1946, Serial No. 710,628

2 Claims. (Cl. 229—53)

1 It is an object of this invention to provide a display bag for containing nuts, popcorn and pretzels or similar commodities, in which the bag will hold the contents in a thin, even layer over the entire transparent portion of the bag and will maintain this relationship whether the bag is in a horizontal or vertical position.

It is a further object of this invention to provide a method for making bags as aforesaid.

The above and other objects will be made clear from the following detailed description taken in connection with the annexed drawings in which:

Fig. 1 is a diagrammatic perspective view illustrating the method of making improved bags.

Fig. 2 is a partial plan showing the rear wall of a completed bag.

Fig. 3 is a section on the line 3—3 of Fig. 2.

Fig. 4 is a section similar to Fig. 3 but showing a modified construction, and

Fig. 5 is a perspective view of the finished bag cut away to illustrate particularly the bottom construction.

For the purpose of this disclosure the term "transparent material" includes not only such truly transparent material as heat sealing cellophane but any heat sealable sheet material which is sufficiently transparent to permit inspection of the contents through a single ply of the material. This includes numerous synthetic films and laminated or coated heat sealable glassine sheets. The films, however, need not be heat sealable since this invention, at least in its article aspect, does not require the heat sealing property. From the standpoint of manufacture, however, heat sealing is greatly to be preferred.

When nut meats or other small confections are sold in small individual packages, it is desirable that the contents of the package be spread out in a relatively thin, even layer so that, so far as possible, the entire contents is subject to inspection. This is easily managed when the package is rigid or in a flexible package so long as the layer occupies substantially a horizontal plane. In the case of a bag formed of all flexible material, however, such display packaging has not been satisfactory for the reason that once the package is removed from the horizontal plane to any approximately vertical position, the contents tends to slide into a thick, compact pile in the bottom of the bag. This distorts the package, adversely affecting its appearance and largely nullifying its display value.

The prior art has recognized this defect and has sought to overcome it by the addition of stiffening members inserted between the plies of

2 the display bag or otherwise secured to the bag. Such stiffening members, however, add greatly to the cost of the package which, after all, must be used almost entirely in the low price retail field where packaging cost bears heavily as a matter of percentage against the packer's selling price of the filled package.

Referring now to Fig. 1, there is illustrated a mandrel 10 around which is formed a tube 12 having a front wall 14 and a rear wall 16. The rear wall 16 contains a longitudinal seam 18. At the forward end of the mandrel 10 a portion 14' of the front wall 14 and a portion 16' of the rear wall 16 are folded over the end of the mandrel 10 to lie against the rear wall 16. The details of machines capable of forming bags in this manner are no part of the present invention, but it may be mentioned that suitable devices of this type are disclosed in the U. S. Patent No. 2,346,219 to Schultz, dated April 11, 1944, and in U. S. Patent No. 2,192,527 to Corcoran, dated March 5, 1940.

The mandrel 10 has formed in its upper surface in contact with the rear wall 16 a plurality of corrugations 20. It will be understood that the mandrel 16 receives suitable vertical support under the front wall 14. A heat bar 22 lies above the rear wall 16 and has in its adjacent face corrugations 24 arranged to mate with the corrugations 20 in the mandrel 10. When heat bar 22 is pressed against the rear wall 16, corrugations 26 (Fig. 2) are formed by the coaction of the grooves 20 of the mandrel 10 and the grooves 24 of the hot bar 22. These corrugations are also formed in the longitudinal seam 18 and in the folded over closure 14' and 16'. At the same time the seam 18 is sealed the portion 16' is sealed to the wall 16 and the portion 14' is sealed to the portion 16'.

When the heated bar 22 is withdrawn from contact with the wall 16 the finished bag is drawn off of the mandrel 10. It then has a corrugated rear wall 16 and a plain front wall 14. The corrugations 26 on cooling will be found to have acquired a permanent set which contributes to a very distinct stiffening of the rear wall 16 sufficient to hold the bag in flattened condition against any sliding of contents to the bottom of the bag when the filled bag is in a vertical position.

While grooves 20 have been illustrated in the mandrel 10, it will be sufficient for many materials to use a mandrel formed of felt or fiber board and having a plane surface facing the rear bag wall 16. Under such circumstances, and

with a suitably chosen mandrel, the corrugations 24 of the hot bar 22 will sufficiently impress themselves upon the material of the mandrel to secure a corrugated effect on the rear bag wall 16.

Fig. 4 illustrates a construction where still more stiffening of the rear wall is required. In this case the bag has a plain front wall 30 and a corrugated rear wall 32. The rear wall 32, however, throughout its entire area is formed of two plies 34 and 36 which, in effect, constitute a longitudinal seam overlapped to the full width of the rear wall. This in turn supplies extra material in the end closure and further stiffens that portion of the bag.

It will be appreciated from the foregoing that, from the standpoint of the article, the corrugations could be formed by the application of starch, glue, or other stiffening material to the rear wall followed by the drying of such material while the rear wall is maintained in a corrugated condition. From the standpoint of manufacture, however, greatly to be preferred.

While I have disclosed certain specific forms of the invention herein for purposes of illustration, it should be understood that many changes and modifications thereof can be made without departing from the spirit of the invention as defined in the appended claims.

I claim:

1. A display bag formed from a single, integral sheet of at least translucent, flexible heat sealable material, said bag having a front wall and a rear

wall, said rear wall containing a seam formed by heat sealing together overlapping margins of said sheet, an end of said bag including portions of said front and rear walls being folded upon and 5 heat sealed to said rear wall, said front wall being optically uninterrupted to permit inspection of the contents, said rear wall including said seam, and said folded end portion being corrugated with a plurality of self-sustaining corrugations serving to hold said rear wall in substantially unchanged relationship to said front wall whether the filled bag occupy a vertical or horizontal plane.

2. A bag as set forth in claim 1 in which the overlap of the margins in the rear wall is sufficient to make the entire rear wall of two ply thickness.

HAROLD F. SHUMANN.
